Primary Examiner — Angela J Lee

(57) **CLAIM**

The ornamental design for a "stand for electronic device," as shown and described.

DESCRIPTION

FIG. 1 is a front perspective view of the stand for electronic device;

FIG. 2 is a front view of the stand for electronic device;

FIG. 3 is a rear view of the stand for electronic device;

FIG. 4 is a right view of the stand for electronic device;

FIG. 5 is a left view of the stand for electronic device;

FIG. 6 is a top view of the stand for electronic device;

FIG. 7 is a bottom view of the stand for electronic device; and,

FIG. 8 is an environmental perspective view including the stand for electronic device.

The broken lines shown in the drawings represent portions of the stand for electronic device or environment that form no part of the claimed design.
